UNITED STATES PATENT OFFICE

JOHN OTTO HEINZE, JR., OF LOWELL, MASSACHUSETTS.

INDUCTION-COIL.

No. 882,198.

Specification of Letters Patent. Patented March 17, 1908.

Application filed September 13, 1907. Serial No. 392,628.

To all whom it may concern:

Be it known that I, JOHN OTTO HEINZE, Jr., a citizen of the United States, residing at Lowell, in the county of Middlesex and State 5 of Massachusetts, have invented certain new and useful Improvements in Induction-Coils, of which the following is a specification, reference being had therein to the accompanying drawing.

10 My invention relates to improvements in induction coils, and the principal object of my invention is to increase the efficiency of a coil like that described and claimed in Letters Patent of the United States for improvements in vibrating mechanism for interrupting currents in spark coils, No. 825,830, and issued to me, July 10, 1906. I accomplish this by providing an iron plate which contacts a soft iron arm mounted 15 upon a base of non-magnetic material, through which projects an electro-magnet beneath a vibrating mechanism, and then in carrying the said iron plate down the side of the spark coil, in order to facilitate the flow 20 of the magnetic current through the magnetic circuit; that is, from one pole of the core, through said arm to the other pole of said core.

Figure 1 is an elevation of my invention as 25 applied to two unit spark coils, the front of the case being broken away to expose diagrammatically the two coils, vibrating vanes, soft iron arms, and thin iron plates. Fig. 2 is a side view in section on line 2—2, in Fig. 35 1. Fig. 3 is a top plan showing the two units or coils stored in the case; each soft iron arm being in metallic contact with its respective thin iron plate. Fig. 4 is a plan in section, on line 4—4 Fig. 2, showing an 40 empty case, the two units shown in Fig. 3 having been removed, while the thin iron plates are left mounted in the case.

I have shown in the drawings the best mode now known to me of embodying the 45 principle of my invention.

A wooden casing 1, having a cover 2, is provided with suitable brackets 3, supporting the same, and, as usual, the primary and secondary terminals, and switch; and is 50 adapted for the reception and removal of, say, two separate coils or units 10, 10', such as shown in Figs. 1, 2 and 3. The inside of the case is divided into two compartments by a partition made up of a sheet of card- 55 board 11; and two thin iron plates 12, 12'. The side of each compartment, opposite the

partition is provided with a thin iron plate 13, 13', also; said partition and said plates engaging and being held in slots in the sides of the casing.

Forming the top of each unit or coil is a piece of insulation 14, 14', as hard rubber, having soft metal arms 15, 16, adjacent to the end of a core 18, 18', which extends up through the insulation; and a vibrating 60 vane 17, 17', overlying the core 18, 18', and portions of soft metal arms 15, 16. An edge portion of each arm 15, 16, is flush with the side of the unit, and when the unit is in position in its respective compartment in the 65 casing, the said edge portion of each arm 15, 16, is in contact with its adjacent iron plate 12, 12', mounted, in this particular construction shown, in the partition or in the side of the compartment opposite to the partition, 70 or in both, as the case may be. Each coil or unit has no magnetic connection with the other.

The operation of my invention will now become plain by reference to Fig. 1. The 75 magnetic currents or lines of force, indicated in dotted lines, and due to the electric currents created by any suitable source of current and passing through the primary winding, and vibrating mechanism of the coil 80 flow from the pole of the core 18, 18', through the vibrating vane 17, 17', the soft metal arms 15, 16, adjacent to the pole of the core, through the thin iron plates 12, 12', 13, 13', 85 contacting the soft metal arms, and then through an air space, to the opposite pole of the core; there thus being completed two magnetic circuits for each core, upon each interruption of the electrical current passing through each particular coil. It is thus ob- 90 vious that the magnetic current or lines of force are greatly aided in their freedom to flow from the soft iron arm to the opposite pole of the core, by the thin iron plate contacting said soft iron arm; the resulting mag- 95 netic field is therefore stronger than heretofore used; the vibrating vane will operate quicker than it otherwise would; and when used in connection with a sparking apparatus, as for a gasoline engine, the resulting 100 sparks produced, will be in greater abundance than will be the case when said plates are dispensed with.

It is to be understood that while it is desirable to have each soft iron arm in magnetic connections with its own individual metallic plate, yet it is to be understood that

the efficiency of a coil or unit is increased even if only one arm is in magnetic connection with a plate in magnetic circuit leading to the opposite pole of the magnet.

5 Desiring to protect my invention in the broadest manner legally possible,

What I claim is:—

1. In a spark coil having an electro-magnet and one or more members of magnetic material, independent of the electro-magnet, and mounted adjacent to the core of the electro-magnet; an iron mass which forms part of a magnetic circuit upon the pole adjacent to said member, through said member, and 15 through said iron mass, to the opposite pole of the core of the electro-magnet.

2. In a spark coil having an electro-magnet and one or more members of magnetic material independent of the electro-magnet, and mounted adjacent to the core of the electro-magnet; an iron mass with which one of said members may be moved and held in magnetic contact, and which forms part of a magnetic circuit from the pole adjacent to 25 said member, through said member, and through said iron mass to the opposite pole of the core of the electro-magnet.

3. In a spark coil having an electro-magnet and one or more members of magnetic material independent of the electro-magnet, and mounted adjacent to the core of the electro-magnet; an iron plate with which one of said members may be moved and held in magnetic contact, and which form part of a 35 magnetic circuit from the pole adjacent to said member, through said member, and through said iron plate to the opposite pole of the core of the electro-magnet.

4. In a spark coil having an electro-magnet and one or more members of magnetic material independent of the electro-magnet, and mounted adjacent to the core of the electro-magnet; iron masses, one for each of said members, and with which said member may 45 be moved and held in magnetic contact; each mass forming a part of a magnetic circuit from the pole adjacent to said member, through said member, and through said iron mass to the opposite pole of the core of the 50 electro-magnet.

5. In a spark coil having an electro-magnet and one or more members of magnetic material independent of the electro-magnet, and mounted adjacent to the core of the electro-magnet; iron plates, one for each of said 55 members, and with which said member may be moved and held in magnetic contact; each plate forming a part of a magnetic circuit from the pole adjacent to said member, through said member, and through said iron 60 plate to the opposite pole of the core of the electro-magnet.

6. In two or more spark coils, each of which has an electro-magnet, and one or more members of magnetic material independent of its electro-magnet and adjacent to one pole thereof; two iron plates which are between any two adjacent spark coils and which are magnetically separated, but each of which is in magnetic contact with its respective member of magnetic material on its spark coil, and which forms part of the magnetic circuit from one pole of the electro-magnet, through said member of magnetic material, to the opposite pole of the said elec- 75 tro-magnet.

7. In two or more spark coils, each of which has an electro-magnet, and two or more members of magnetic material independent of its electro-magnet and adjacent to one pole thereof; two iron plates which are between any two adjacent spark coils and which are magnetically separated, but each of which is in magnetic contact with its respective member of magnetic material on its spark coil, and which forms part of the magnetic circuit from one pole of the electro-magnet through said member of magnetic material to the opposite pole of said electro-magnet; and an iron plate for each other 90 member of magnetic material, and forming a part of the magnetic circuit of its respective electro-magnet.

In testimony whereof I affix my signature in presence of two witnesses.

JOHN OTTO HEINZE, JR.
